(57) **CLAIM**

The ornamental design for a cable staple, as shown and described.

DESCRIPTION

FIG. 1 is a top perspective view of a cable staple of the present invention.

FIG. 2 is a front view of a cable staple of the present invention.

FIG. 3 is a rear view of a cable staple of the present invention.

FIG. 4 is a right side elevation view of a cable staple of the present invention.

FIG. 5 is a left side elevation view of a cable staple of the present invention.

FIG. 6 is a top view of a cable staple of the present invention; and,

FIG. 7 is a bottom view of a cable staple of the present invention.

1 Claim, 3 Drawing Sheets
